SAFE SECURITY MARKER

Anthony J. Daniels, Memphis, Tenn.

Application January 27, 1959, Serial No. 54,358

Term of patent 14 years

(Cl. D1—2)

(Granted under Title 35, U.S. Code (1952), sec. 266)

Figure 1 is a front elevational view of a safe security marker embodying my new design;

Figure 2 is a rear view of the same; and

Figures 3 and 4 are, respectively, side and bottom plan views thereof.

The lined shading in Figs. 1 and 2 indicates contrasting colors. The essential features of the design are shown in full lines.

The invention described herein, if patented, may be manufactured and used by or for the Government for governmental purposes, without the payment to me of any royalty thereon.

I claim:

The ornamental design for a safe security marker, substantially as shown and described.
